UNITED STATES PATENT OFFICE.

JOSEPH E. ROCHELTE, OF NORWICH, CONNECTICUT.

FILLING DETECTOR FOR LOOMS.

Application filed September 27, 1923. Serial No. 665,038.

To all whom it may concern:

Be it known that I, JOSEPH E. ROCHELTE, citizen of the United States, residing at Norwich, in the county of New London and State of Connecticut, have invented certain new and useful Improvements in Filling Detectors for Looms, of which the following is a specification.

The present invention relates to filling detectors or feeler mechanisms for effecting a change in the operation of a loom when the filling in the active shuttle has become nearly exhausted.

Detector mechanisms of various types have heretofore been proposed for feeling into the shuttle during the operation of the loom, and upon the occurrence of substantial exhaustion of the filling in the shuttle, setting into operation mechanism for effecting replenishment of the filling supply. In some types, the detecting means has consisted of two members, one an impinging member to contact with the filling in the shuttles, and the other a penetrating member to sink into the filling on each detecting beat-up movement of the lay and upon the occurrence of substantial exhaustion of filling, these members have cooperated to initiate filling replenishment.

In detector mechanisms comprising an impinging member and a penetrating member it is desirable that there should be capacity for the relative adjustment of the two members toward and from the lay in order to determine the most advantageous degree of penetration of the penetrating member with respect to the particular yarn or filling on the bobbin or carrier in the shuttle.

An important feature of the present invention therefore consists in providing a filling detector of the impinging and penetrating type with means for relatively adjusting the two members bodily toward and from the lay.

As well understood by those familiar with those devices, the detecting action and initiation of filling replenishment must be effected in a very small fraction of time, during the detecting beat of the lay. Therefore, simplicity of construction and operation conduce to a more accurate accomplishment of the desired end.

Another important feature of the invention, therefore, consists in operatively positioning the means for initiating re-

plenishment by simple and positive means, which, in the embodiment of the invention here illustrated, comprises a rocker in the form of a bell crank which may be turned upon its axis through a small arc when the penetrating member strikes the more dense substance of the filling carrier or bobbin.

Another object of the invention is to generally simplify and improve devices of the above kind whereby the same may meet with all of the requirements for a successful commercial use.

Other features of the invention will be hereinafter described, in connection with the illustrated embodiment of the invention, and then definitely set forth in the claims.

In the drawings:

Figure 1 is a view, partly in plan and partly in section of the filler detector, showing the action of the impinging and penetrating members when a working supply of filling is present in the shuttle.

Figure 2 is a plan view, similar to that of Figure 1, showing the position of parts on the beat-up movement when the filling is substantially exhausted.

Figure 3 is a side elevational view of the detector with the parts in their normal position.

Figure 4 is a transverse sectional view taken substantially upon the line 4—4 of Figure 1.

Figure 5 is an enlarged perspective view of the controller actuated lever.

Figure 6 is a view similar to Figure 5 of the slide block which carries the bell crank rocker.

Figure 7 is a perspective view of the bell crank rocker.

The detecting mechanism of the present invention is adapted to be applied to a so-called filling replenishing or automatic loom, wherein, upon substantial exhaustion of the filling in the shuttle, means are set in operation to effect a replenishment of the filling. The replenishment mechanism and its general characteristics and operations, as well as the parts for initiating its operation under the command of the detecting mechanisms are well understood by those skilled in the art, and detailed explanation thereof is unnecessary.

The shuttle S is provided with an opening 5 in its side wall and the shuttle box 110 will have its front wall provided with an opening, the said openings of the wall of

the shuttle and the shuttle box being adapted to register when the shuttle is properly positioned in said box for the action of the detector mechanism. These features also are 5 common and well understood.

The filling detector comprises a stand or base plate 6 which may be properly secured to a suitable portion of the loom frame, in which the detector is to be used by the means 10 of screws or the like, and is provided with bearing portions 7 and 8 in which is mounted the feeling carrier 9, the forwardly extending stem portion of which is under the control of a suitable spring 10 normally tending 15 to force the feeler carrier rearwardly or toward the lay. In the present instance of the invention, the feeler is shown as a slide and the spring 10 surrounds the stem portion of the feeler and at one end is seated against 20 the bearing 7 and at the other end against the slide block 11 that is fixed upon the stem portion of the feeler 9 as clearly shown in the several views.

The term "feeler slide" is herein employed 25 in its broad sense as a part for carrying the feeler members and movable toward and away from the front of the loom.

The feeler slide 9 has at its rear portion, an impinging member 12, in the form of a 30 laterally directed end of said feeler slide, and which, when the shuttle is in the box at the detecting side of the loom is adapted to enter and contact with the filling or filling carrier in the shuttle.

35 Extending through the impinging member 12 of the feeler slide, is the penetrating member 13, the penetrating end portion of which is preferably formed by reducing the rear end of said penetrating member so as 40 to provide a shoulder as at 14 for limiting the penetrating movement of the member 13 through the head 12, opposite side of the free end portions of the needle thus produced being bevelled so as to provide a knife edge, as 45 at 15.

Rising from the slide block 11 of the feeler 50 slide rod 9 is a lug 16, in which is mounted the stud 17, on which the bell crank rocker 18 is pivotally mounted. As shown in the several views, the lug 16 is provided upon the inner end of the block 11, and the stud 17 extends transversely of the base plate 6 and through a central opening 19 provided at the juncture of the arm of the bell crank rocker 55 18, said rocker being disposed with an upwardly extending arm, and a forwardly projecting lower arm. The free end portion of the lower arm of the rocker 18 is provided with a notch as at 20, which is adapted, at 60 times, to engage a controller operating lever 21, for initiating filling replenishment when such feeler is moved toward the front of the loom while engaged with the controlling operator lever 21.

65 In order to control the operative or in-

operative position of the rocker 18 with respect to the controller operating lever 21, a coiled spring 22 is provided upon the stud 17 between the lug 16 and said rocker 18, one end of the spring being passed into an opening 23 provided in the lug 16, and the other end of said spring being passed into an opening 24 provided in the lower arm of said rocker 18 whereby the spring 22 normally causes the rocker to swing to a position wherein the lower arm of the latter is normally horizontally positioned in a plane above the rearwardly extending sharpened end 25 of the lever 21.

The upwardly extending arm of the rocker 18 is provided with a transverse opening 26 in which is secured a stud 27 and this stud is provided with a transverse opening through which the adjacent forward end of the penetrating member or rod 13 projects. As shown clearly in Figure 3, the forward end of the penetrating member 13 is upwardly offset as at 28 so that the forward end portion 29 of the penetrating member 13 is positioned in the proper plane 90 to pass through the opening of the stud 27. This end 29 is screw threaded as shown to receive nuts 30 thereon at opposite sides of the stud 27, whereby the penetrating member is rigidly fastened to the stud 27. Obviously, the stud 27 may have a reduced end portion which enters the opening 26 and which is threaded for reception of a nut 31, whereby the stud 27 is rotatably mounted in the upwardly extending arm of the rocker 18, and whereby the device may be constructed at this point for being readily assembled or repaired. Also, by loosening the nuts 30, the position of the penetrating member 13 relative to the impinging arm or head 12 may be adjusted, after which the adjustment may be secured by again tightening said nuts 30.

The bearing 7 is preferably formed of an integral structure, while the bearing 8 may be provided with a removable cover plate held in place by means of screws or the like as at 32, thus enabling ready assembling of the feeler slide rod 9 and the base plate 6.

The lever 21 is of general bell crank form and pivotally mounted upon a vertical stud 33 fixed to the base plate 6 rearwardly of the rocker 18 for swinging movement in a horizontal plane, the inwardly extending arm of the lever 21 being formed with the rearwardly directed tooth 25 above mentioned, and the other or forwardly projecting arm of said lever 21 being provided with perforations as at 34 for adjustable connection with the usual controller operating rod. The lever 21 is yieldingly swung to and held in its normal operative position by means of a helical tension spring 35, connected to the inwardly extending arm of said lever 21, as at 36, and having its outer 120 125 130

end attached as at 37 to a post upon the rear portion of the plate 6. The movement of the lever 21 under the influence of the spring 35 is limited by the downturned end portion 38 of the forwardly projecting arm of said lever 21, which downturned end 38 is adapted to engage the adjacent edge of the plate 6 when the lever is thus positioned with the tooth 25 parallel with the longitudinal axis of the plate 6 as shown in Figure 1.

From the above description, it will be seen that the spring 22 not only serves to hold the rocker 18 in a normal position with the forwardly extending arm thereof out of the path of the tooth 25 of the lever 21, but also serves to hold the penetrating member 13 in its rearward position wherein the same is projected with respect to the impinging member or head 12.

From the above description, it is apparent that the spring 10 will hold the arm or head 12 against filling as shown in Figure 1, while the spring 22 will cause the penetrating member 13 to be projected for penetrating said filling of the filling carrier. However, when the filling becomes practically exhausted as shown in Figure 2, and the penetrating member engages the more dense substance of the bobbin or filling carrier and is thereby moved forward on the beat-up movement of the lay, the penetrating member turns the rocker 18 upon its pivotal mounting 17 and thereby moves the lower arm of said rocker 18 to bring its bifurcated end portion as at 20 into lowered position for engaging the controller operating lever 21, or, specifically, for engaging the tooth 25 of said lever 21, when the detector or feeler slide is moved toward the front of the loom.

From the above description, it will be apparent that upon turning movement of the rocker 18, due to the penetrating member of the detector engaging the dense substance of the filler carrier or bobbin, such rocker is turned upon its axis to thereby position the lower arm of the rocker 18 operatively and initiate filling replenishment upon the forward movement of the detector.

The construction is simple and effective and the parts so related that within the small space of time allowed for the action of the detector, upon substantial exhaustion of filling, the parts may resume the desired relation for initiating filling replenishment.

What I claim as new is:

1. A filling detector for filling replenishing looms comprising, in combination, an impinging member, a slide block fixed on said impinging member and having an upstanding lug at the inner end thereof, a bell crank rocker pivotally carried by said lug for vertical swinging movement and having the arms thereof respectively extending up-

wardly and forwardly, a controller operating lever having a rearwardly extending tooth arranged in the same vertical plane as the bell crank rocker, a penetrating member having its forward end pivotally connected with the upper end of the upwardly extending arm of the rocker, means for normally swinging the rocker to a position wherein its forwardly projecting arm is raised above the path of said lever tooth with the penetrating member projected, and whereby said rocker is permitted to turn upon displacing the penetrating member relative to the impinging member for moving the forwardly extending arm of the rocker downwardly in the path of said lever tooth, said controller operated lever being mounted to swing in a horizontal plane, and yieldable means to normally swing the lever to a position wherein the tooth of the same is disposed in the path of the forwardly projecting arm of said rocker when the latter arm is lowered.

2. A filling detector for filling replenishing looms comprising, in combination, an impinging member, a slide block fixed on said impinging member and having an upstanding lug at the inner end thereof, a bell crank rocker pivotally carried by said lug for vertical swinging movement and having the arms thereof respectively extending upwardly and forwardly, a controller operating lever having a rearwardly extending tooth arranged in the same vertical plane as the bell crank rocker, a penetrating member having its forward ends pivotally connected to the upper end of the upwardly extending arm of the rocker, means for normally swinging the rocker to a position wherein its forwardly projecting arm is raised above the path of said lever tooth with the penetrating member projected and whereby said rocker is permitted to turn upon displacing the penetrating member relative to the impinging member for moving the forwardly extending arm of the rocker downwardly in the path of said lever tooth, the pivotal connection between the penetrating member and the bell crank rocker embodying an inwardly extending stud journaled in the upper end of the upwardly extending arm of the rocker, and having a transverse opening through which the forward end of the penetrating member slidably extends, said forward end of the penetrating member being threaded at opposite sides of said pivot stud, and nuts on said threaded end portion of the penetrating member for securing the latter to said pivot studs, and for permitting adjustment of the penetrating member longitudinally.

3. A filling detector for filling replenishing looms comprising a base plate having slide bearings, an impinging member having a rod portion slidably mounted in said bear-

ing and provided with a laterally extended rear end portion forming an impinging head, said impinging head having an opening therethrough, a slide block resting upon the 5 base plate and fixed upon the rod portion of the impinging member, a spring encircling the rod portion of said impinging member between one of said bearings and said slide blocks, said slide blocks being provided with an upwardly extending lug 10 provided with a horizontal lateral stud, a bell crank rocker pivotally mounted for vertical swinging movement upon said stud, and embodying upwardly extending and forwardly 15 extending arms, the forwardly extending arm of said rocker being notched at its free end, a penetrating member having a reduced rear end portion slidably mounted in the opening of the impinging head and having 20 its forward end portion offset upwardly, a pivot stud journaled in the upper end of the upwardly extending arm of the rocker and extending laterally from the latter in a horizontal position, the upwardly offset end

portion of the penetrating member being 25 slidably extending through the projecting portion of said pivot stud, nuts threaded upon the penetrating member at opposite sides of the pivot stud for securing the latter together and for permitting adjustment of 30 the penetrating member longitudinally, a vertical stud rigid with and projecting upwardly from the base plate, a bell crank lever pivoted upon said vertical stud and having inwardly and forwardly projecting arms, a rigid rearwardly extending tooth upon the inwardly extending arm of said lever, and yieldable means normally tilting the rocker for projecting the penetrating member and disposing the forwardly projecting arm of the rocker above the tooth of 35 said lever, and for permitting tilting of the rocker upon forward displacement of the penetrating member relative to the impinging member for positioning the forwardly projecting arm in the path of said tooth.

In testimony whereof I affix my signature.
JOSEPH E. ROCHEILLE.
